VIRGINIUS Z. CARACRISTI, OF BRONXVILLE, NEW YORK, ASSIGNOR TO LOCOMOTIVE PULVERIZED FUEL COMPANY, OF NEW YORK, N. Y., A CORPORATION OF DELAWARE.

MEANS FOR FEEDING FUEL TO COMBUSTION-CHAMBERS.

1,336,125.

Specification of Letters Patent.

Patented Apr. 6, 1920.

Application filed January 27, 1915. Serial No. 4,691.

To all whom it may concern:

Be it known that I, VIRGINIUS Z. CARACRISTI, a citizen of the United States, and a resident of Bronxville, in the county of 5 Westchester and State of New York, have invented certain new and useful Improvements in Means for Feeding Fuel to Combustion-Chambers, of which the following is a specification.

10 This invention relates to improvements in means for feeding fuel to combustion chambers, and has for its object to provide an improved construction by which the maximum amount of travel in the minimum 15 amount of space is obtained, after which the fuel and air mixture under combustion is subjected to further combustion in a manner heretofore well known. My improved fuel feeder is adapted for use in metallurgical furnaces, steam generators, and other 20 similar uses.

With these and other objects in view, my invention consists of the novel features, construction and arrangement of parts, 25 hereinafter more fully described and pointed out in the claims.

In the drawings,

Figure 1 is a vertical longitudinal section of the improved apparatus, in this case applied to a small forging furnace;

Fig. 2 is a vertical section taken on the line 2—2 of Fig. 1; and

Fig. 3 is a vertical section of a slightly modified form of construction.

35 Similar reference characters indicate corresponding parts throughout the several views.

Referring to the drawings, and more particularly to Fig. 1 thereof, a small furnace 40 10 substantially rectangular in shape, or which may be of another shape more adapted to its particular use, is provided with a chimney 12, in a manner well known. In the front portion 15 of the furnace, a 45 combustion chamber 16 is provided, which is circular in cross-section, as indicated by 17 in Fig. 2, the diameter of the circular cross-section being smaller by almost one-half of the height of the furnace 10 at the 50 forward portion 18 thereof. This is the case in the embodiment shown, but changes in the relative proportions may be made, depending upon the capacity or particular use of the furnace, generator or the like. The 55 combustion chamber 16 is elongated in the

form of a cylinder away from the furnace 10, and is closed at its front end by a wall 20. An opening 21 is provided in the chamber 16, communicating with a cylindrical channel 22, the lower wall 23 of which is formed 60 tangential with the circular inner surface 17 of the said chamber.

Projecting into the said channel 22 is a feeding nozzle 25 supported on trunnions 26 by a shaft, the said shaft being provided 65 at one end with a manipulating handle 28. The feeding nozzle is supplied at its rear portion 29 with fuel and air in suitable proportions, the said air being a current of high velocity, the said fuel being in the form 70 of pulverized coal or oil or other suitable material, and as the same is fed into the furnace through the said nozzle 25, it is directed tangential to the inner surface of the said combustion chamber, and in a direction 75 along the length thereof, from the front wall 20 to the other end 30, and into the furnace 10. As the nozzle 25 is inclined in relation to the axis of the combustion chamber, the stream of fuel and air is directed 80 therethrough in a spiral or helical path of greater or less length according to the lateral and longitudinal inclination of the nozzle to the axis of the furnace, that is, the inclination in a plane passed through the 85 axis, and in a plane perpendicular to the axis, respectively. So, when the nozzle is directed at a greater angle in relation to the axis of the combustion chamber, the number of convolutions will be larger than when the 90 angle of the nozzle is less. Referring to Fig. 1, it will be noticed that the mixed fuel and air, entering the combustion chamber, owing to its incoming velocity from the nozzle 25, takes the helical path indicated by 95 the dotted line 31, until it passes out of the end 30 into the chamber 10, where, owing to its not being closely confined, the products of combustion pass through the furnace, which is of larger volume than the combustion 100 chamber, in the usual manner.

A longitudinal channel or trough 32 is provided in the bottom of the combustion chamber 16 for the portion of its length beyond the nozzle opening 21, in which is 105 caught any of the products of combustion, which may fall to the bottom of the said chamber, and a blast of compressed air is directed therein through a pipe 33, to remove the said products of combustion.

In the modified form shown in Fig. 3, there is no longitudinal channel provided, the surface of the chamber being unbroken beyond the nozzle opening.

- 5 From the above it will be seen that the combustion chamber is adapted to contain a long stream of fuel by reason of the convolutions, which the stream must take within the combustion chamber, due to its velocity 10 and its tendency to hug the wall. As different fuels and fuels under different conditions require a different element of time for combustion, the time which the particular fuel is in the combustion chamber may be 15 shortened or lengthened by varying the angle of the feeding nozzle. In this way, just the proper element of time is allowed to provide for complete combustion, and the products of combustion having thereby obtained 20 a maximum temperature can perform useful work without any loss due to being cooled below the oxidation temperature, and incidental loss due to the combustion not being completed before this point is reached.
- 25 I have illustrated and described preferred and satisfactory forms of my invention, but it is obvious that changes may be made therein, without departing from the spirit and scope thereof, as defined in the appended claims.

I claim:—

1. In a furnace, a main chamber and a preliminary combustion chamber having an open end opening directly into the main chamber, said preliminary combustion chamber extending horizontally from the main chamber with its remote end closed, a nozzle opening into said combustion chamber and inclined both laterally and longitudinally to the axis of said combustion chamber, and means for supplying said nozzle at a point spaced from its mouth with fuel and with a current of air, the said lateral angle of said nozzle being so large that the said current 40 of air and the fuel are caused to impinge upon the said wall along the length of the combustion chamber in a helical path tangentially to the wall before the combustion 45 of said fuel has been completed.
- 50 2. In a device of the character described, a combustion chamber having an inner wall having a circular cross section, means for injecting fuel at a high velocity tangential to said inner wall, and at an inclination to

the axis of said chamber to give the same 55 a helical path within said wall, and means for changing the inclination of said injecting means.

3. In a device of the character described, a combustion chamber having a circular inner surface and provided with an opening tangential to said inner surface, means in said opening for directing fuel at a high velocity in a path inclined to the axis of said chamber, and tangential to said inner surface, and a means for changing the angle of inclination of said directing means.

4. In a device of the character described, a combustion chamber having an inner wall having a circular cross section, means for injecting fuel in a path inclined to the axis of said wall, and substantially tangentially to said inner wall, to give the same a helical path within said wall and means for changing the inclination of said injecting means, 75 means in said wall for receiving the falling products of combustion and means for removing said fallen products of combustion.

5. In a furnace, a main chamber and a preliminary combustion chamber having an open end opening directly into the main chamber, said preliminary combustion chamber extending horizontally from the main chamber with its remote end closed, a nozzle opening into said combustion chamber 85 and inclined both laterally and longitudinally to the axis of said combustion chamber, and means for supplying said nozzle at a point spaced from its mouth with fuel and with a current of air, the said lateral angle 90 of said nozzle being so large that the said current of air and the fuel are caused to impinge upon the said wall along the length of the combustion chamber in a helical path tangentially to the wall before the combustion 95 of said fuel has been completed, the said nozzle having a substantially straight axis, said current of air and of fuel being directed in the said nozzle in a substantially straight line path until they emerge into said chamber. 100

In testimony that I claim the foregoing as my invention, I have signed my name in presence of two subscribing witnesses.

VIRGINIUS Z. CARACRISTI.
